UNITED STATES PATENT OFFICE.

KARL SLOAT, OF SCRANTON, PENNSYLVANIA.

STOP-MOTION.

1,099,772.

Specification of Letters Patent.

Patented June 9, 1914.

Application filed January 13, 1914. Serial No. 811,828.

To all whom it may concern:

Be it known that I, KARL SLOAT, a citizen of the United States, and a resident of Scranton, in the county of Lackawanna and 5 State of Pennsylvania, have invented a new and Improved Stop-Motion, of which the following is a full, clear, and exact description.

The object of the invention is to provide a 10 new and improved stop motion designed for use on reeling machines and similar machines, and arranged to quickly and positively stop the reel in case of the breaking of a thread or yarn, or the running out of 15 the yarn from its spool, which requires no fine adjustment or sensitive balancing by skilled workmen, and to prevent the parts from being actuated by mere vibration incident to the running of the machine. 20 In order to accomplish the desired result, use is made of a pivoted lifting arm adapted to lift the reel out of engagement with the driving gear, pivoted drop arms having eyes 25 for the threads or yarns to pass through to normally hold the drop arms in raised inactive position, and actuating means controlled by the said drop arms and controlling the said lifting arm to move the latter into active position on the release of a drop arm 30 by this thread or yarn.

A practical embodiment of the invention is represented in the accompanying drawings forming a part of this specification, in which similar characters of reference indicate corresponding parts in all the views.

Figure 1 is a side elevation of the stop motion as applied to a silk reeling machine; Fig. 2 is a cross section of the same on the line 2—2 of Fig. 1; Fig. 3 is a similar view 40 of the same with the parts in position after a drop arm is released by its thread or yarn and the reel is stopped from rotating; Fig. 4 is a sectional plan view of the same on the line 4—4 of Fig. 2; Fig. 5 is a cross section 45 of part of the stop motion and showing more particularly one of the drop arms in dropped position; Fig. 6 is a cross section of part of the reeling machine, the section being on the line 6—6 of Fig. 1; and Fig. 7 is a front elevation of part of the mechanism for imparting a reciprocating motion to the actuating slide.

The reeling machine on which the stop motion is applied is mounted on a suitably constructed frame A in which is journaled a

main shaft B provided at one end with a pulley B' connected by a belt with other machinery for imparting a continuous rotary motion to the said main shaft B. On the main shaft B is secured a driving pulley B² normally in frictional contact with the peripheral face of a pulley C secured on the shaft D' of the reel D on which the threads or yarns E are wound, the threads or yarns unwinding from suitable bobbins or spools E', as plainly indicated in Figs. 1 and 2.

The reel shaft D' is journaled at its ends in open bearings A' and A² held on the ends of the main frame A, thus permitting removal of the filled reel from the machine 70 and lifting of the pulley C out of driving engagement with the pulley B² to stop the rotation of the reel D and consequently the winding up of the yarns or threads E on the said reel in case a thread or yarn is 75 broken or the thread runs out on a spool E', as hereinafter more fully explained.

Each of the threads or yarns E passes through an eye F' of a drop arm F normally disposed in a vertical position and 80 resting against a rod G attached to the frame A and in front of which passes the corresponding thread E (see Fig. 2). The drop arm F is provided with a heel F² pivoted on a bearing H attached to a shaft or 85 rod H' mounted to slide in the direction of its length in bearings A³, A⁴ forming parts of the main frame A. The shaft H' is normally held in position, as shown in Fig. 1, by the action of a spring H² resting at one 90 end against the bearing A³ and abutting at its other end on a pin H³ held on the shaft H'. The left-hand end of the shaft H' normally supports a starting lever I extending transversely and fulcrumed at I' on the 95 main frame A, and the pivotal end of the starting lever I is provided with fork members I², I³, of which the member I³ is provided with an adjusting screw I⁴, and the fork members straddle the lower end of a 100 lifting arm J fulcrumed at its lower end at J' on the main frame A. The upper end J² of the lifting arm J is in close proximity to the peripheral face of the reel pulley C, as plainly indicated in Fig. 2, but when the shaft H' is moved to the right and from under the lever I then the latter in swinging downward causes the screw I⁴ to impart a 105 swinging motion to the lifting arm J in the direction of the arrow a' so that the top J² 110

of the said lifting arm J engages the peripheral face of the reel pulley C and lifts the latter and with it the reel so that the pulley C moves out of driving engagement 5 with the pulley B² (see Fig. 3). When this takes place the reel D comes to a standstill.

In order to move the shaft H' to the right against the tension of the spring H² and with a view to move the left-hand end of its 10 shaft out from under the lever I, the following arrangement is made: The heel F² of the drop arm F is provided with a rearward extension F³ (see Figs. 2, 3, 4 and 5) normally out of the path of blocks K secured 15 on a slide K' arranged parallel to the shaft H' and mounted to slide in the direction of its length in the bearings A³, A⁴ previously mentioned (see Figs. 1 and 4).

The slide K' receives a continuous reciprocating motion from the reel shaft D' as long as the latter is driven and for this purpose the following arrangement is made: On the slide K' is secured a collar L (see Figs. 1 and 6) by the use of a set screw L', and on the collar L is arranged a rearwardly-extending pin L² engaging a fork N' forming part of the lower end of a lever N fulcrumed at N² on the main frame A. The upper end of the lever N is provided 25 with a fork N³ engaging a crank arm O held on the hub O' of a gear wheel O² journaled in suitable bearings arranged on the main frame A. The gear wheel O² is in mesh with a pinion P having a hub P' journaled in suitable bearings on the main frame A, and on the hub P' is secured a crank arm P² engaging a cross head Q' formed on or attached to a traverse bar Q mounted to slide in suitable bearings arranged on the 30 main frame A. The traverse bar Q is provided with eyes Q² through which pass the threads or yarns E after passing through the eyes F' so that the threads E are properly fed onto the reel D in the usual manner. The pinion P is provided with a bevel gear wheel R (see Figs. 1 and 6) in mesh with a bevel gear wheel R' secured on a shaft R² journaled in suitable bearings arranged on the main frame A, and on the said shaft R² 40 is secured a gear wheel R³ in mesh with a pinion R⁴ secured on the reel shaft D'. Now when the reel shaft D' is rotated as previously explained, then a rotary motion is transmitted by the pinion R⁴ and gear wheel R³ to the shaft R² which by the gear wheels R', R, P and O² rotates the crank arm O so that a swinging motion is given to the lever N which by its fork N' and the pin L² imparts a sliding motion to the slide K'. 45 From the foregoing it will be seen that as long as the reel shaft D' is rotated a sliding motion is given to the slide K' and in case one of the drop arms F is released by its thread or yarn E and swings downward 50 into the position shown in Fig. 5 then the

extension F³ of this drop arm F passes into the path of the adjacent block K of the reciprocating slide K' whereby the block K imparts a sliding movement to the extension F³ and consequently to the bearing H and 70 the shaft or rod H' to lift the latter from the left to the right in the direction of the arrow b' thus moving the left-hand end of the rod or shaft H' out from under the starting lever I. When this takes place the latter swings downward and thereby imparts a swinging motion to the lifting arm J so that the latter raises the pulley C out of engagement with the pulley B² and consequently further rotation of the reel D ceases. 80 It will be noticed that when rotation of the reel D ceases the reciprocating motion of the slide K' ceases owing to the fact that the slide is actuated from the shaft D' by the mechanism above described. 85

In order to prevent the rod or shaft H' from turning in its bearings, it is provided with a depending arm H⁴ having a fork H⁵ straddling a tension rod S, and in order to prevent the slide K' from turning an 90 arm K² depends from the slide and is provided with a fork K³ straddling a tension rod S'. The tension rods S and S' are attached to the main frame A and the threads or yarns E pass around the said tension 95 rods prior to passing to the eyes F' of the drop arms F, as will be readily understood by reference to Fig. 2.

It is understood that in case any one of the threads or yarns E breaks or the thread 100 runs out from the corresponding spool E' then the corresponding drop arm F swings downward and in doing so its extension F² moves into the path of the adjacent block K of the slide K'. As the slide K' reciprocates continually it imparts motion to the extension F³ of the drop arm F whereby the shaft H' is moved to the right and out from under the starting lever I. The latter now swings downward and imparts a swinging motion to the lifting arm J in the direction of the arrow a' to lift the pulley C out of engagement with the pulley B² and consequently further rotation of the reel D ceases. 105 When the broken thread has been mended and replaced in the eye F' of the returned drop arm F then the operator swings the starting lever I upward so that the member I² of the said lever imparts a rearward swinging motion to the lifting arm J to cause the latter to lower the pulley C until this pulley is again in frictional contact with the peripheral face of the continually rotating pulley B². A rotary motion is now again given to the reel D and the slide 110 K' is reciprocated. 115

It is understood that when the drop arm F is swung back into vertical position and the lever I is raised the left-hand end of the shaft H' again moves under the lever I 120 130

by the action of the spring H^2 so as to support the starting lever I in its normal position.

Having thus described my invention, I claim as new and desire to secure by Letters Patent:

1. A stop motion for reeling machines and like machines, comprising a reciprocating actuating slide, a drop arm normally held 10 out of the path of the said slide by a yarn, a shaft on which the said drop arm is mounted to swing, the said shaft being mounted to slide, a starting lever adapted to rest on one end of the said shaft, a lifting 15 arm controlled by the said starting lever and adapted to lift the reel of the reeling machine out of driven position relative to its driving means.

2. A stop motion for reeling machines and 20 like machines, comprising a reciprocating slide having actuated blocks, a shaft mounted to slide in the direction of its length and arranged parallel to the said slide, a series 25 of drop arms each pivoted on the said shaft and having an eye for the passage of a yarn, and a weighted heel to impart a swinging motion to the drop arm when the latter is released by its yarn, the said heel being normally out of the path of a slide block 30 and the said heel being adapted to swing into the path of the block on the drop arm being released, and a stopping device controlled by the lengthwise movement of the said shaft.

3. A stop motion for reeling machines and like machines, comprising a reciprocating slide having actuated blocks, a shaft mounted to slide in the direction of its length and arranged parallel to the said slide, a 40 series of drop arms each pivoted on the said shaft and having an eye for the passage of a yarn and a weighted heel to impart a swinging motion to the drop arm when the latter is released by its yarn, the 45 said heel being normally out of the path of a slide block and the said heel being adapted to swing into the path of a block on the drop arm being released, a starting lever normally supported by the said shaft, 50 a lifting arm mounted to swing and controlled by the said starting lever, and a driving gear having a member adapted to be engaged by the said lifting arm to render the said member inactive.

4. In a reeling machine, the combination 55 of a driving pulley, a reel having a pulley

normally in frictional contact with the said driving pulley, a lifting arm mounted to swing and adapted to engage the peripheral face of the said reel pulley to lift the latter 60 out of driving engagement with the said driving pulley, a starting lever controlling the said lifting arm, supporting means for the said starting lever and releasing means for the said supporting means and controlled by the yarns wound on the said reel to move the said supporting means out of engagement with the said starting lever to allow the latter to drop.

5. In a reeling machine, the combination 70 of a driving pulley, a reel having a pulley normally in frictional contact with the said driving pulley, a lifting arm mounted to swing and adapted to engage the peripheral face of the said reel pulley to lift the latter 75 out of driving engagement with the said driving pulley, a starting lever controlling the said lifting arm, a shaft mounted to slide and supporting at one end the said starting lever, a series of drop arms mounted to swing on the said shaft and having eyes for the passage of the yarns and weighted heels, and a reciprocating slide having means adapted to engage the heel of a dropped arm to impart a sliding motion 85 to the shaft for releasing the starting lever.

6. In a reeling machine, the combination 90 of a driving pulley, a reel having a pulley normally in frictional contact with the said driving pulley, a lifting arm mounted to swing and adapted to engage the peripheral face of the said reel pulley to lift the latter 95 out of driving engagement with the said driving pulley, a starting lever controlling the said lifting arm, a shaft mounted to slide and supporting at one end the said starting lever, a series of drop arms mounted to swing on the said shaft and having eyes for the passage of the yarns and weighted heels, a reciprocating slide having means 100 adapted to engage the heel of a dropped arm to impart a sliding motion to the shaft for releasing the starting lever, and means controlled by the said reel for imparting a reciprocating motion to the said slide. 105

In testimony whereof I have signed my name to this specification in the presence of two subscribing witnesses.
